COMBINED BASKETBALL GOAL WITH SUPPORT AND GROUND ENGAGING UNIT

Joseph L. Fortin, 1132 W. 3rd Ave.,
Columbus, Ohio 43212

Filed July 13, 1971, Ser. No. 162,320

Term of patent 14 years

Int. Cl. D21—02

U.S. Cl. D34—5 VV

FIG.2

FIG.3

FIG.1

Fig. 1 is a side elevational view of a combined basketball goal with support and ground engaging unit showing my new design.

FIG. 2 is a perspective view thereof; and

FIG. 3 is a front elevational view thereof.

I claim:

The ornamental design for a combined basketball goal with support and ground engaging unit, as shown and described.
